UPPER PART FOR SPINDLES

Wilhelm Stahlecker, Stuttgart-Bad Cannstatt, Germany, assignor to Vereinigte Kugellager-fabriken A. G., Schweinfurt, Werk Bad-Cannstatt, Germany, a corporation of Germany

Application December 21, 1939, Serial No. 310,308
In Germany January 4, 1939

2 Claims. (Cl. 57—130)

This invention relates to spindles used on spinning or twisting machines and more particularly to tubular upper parts of such spindles, held by the spindle blade, and leaving a free space between blade and tube.

Spindle upper parts are known which consist of tubes connected rigidly with the whirl of the spindle or consisting in one piece with the whirl itself. In the latter case such upper parts are called tubular whirls. The disadvantage of such designs is the difficulty to manufacture them with enough accuracy, so as to produce a true running spindle.

The usual way of putting a wooden plug upon the spindle blade has the drawback that the wood due to its nature is inclined to get warped by the change of heat and humidity.

The present invention intends to avoid such difficulties in applying a tubular metallic upper part for the spindle, supported by the whirl and the spindle blade.

The nature of the invention will be understood more clearly from the drawing and the accompanying description, showing a preferred form of the invention.

In the drawing:

Fig. 1 is a view of the improved spindle upper part illustrated partly in section.

Fig. 2 is an axial, sectional view illustrating the middle of an upper part, consisting of two tubular parts.

Fig. 3 is a vertical, sectional partial view of another form of spindle upper part.

The present improved upper part comprises, in general, an axial support or spindle blade and a tubular part held between the whirl and a button connected with the spindle blade. The connection for all those parts is made by a press fit.

Referring to the drawing *e* designates the central support or spindle blade for the tubular upper part *a*, consisting of a metallic tube, made of steel or light metal. This tube is preferably shaped to conical form, in order to be able to carry paper or cardboard tubes and the like in the usual way. The tube *a*, at its lower end is pressed upon the neck *b* of the whirl *c*. At or near its upper end *d*, the tube is held by the button *f*, which in turn is pressed upon the end of the spindle blade *e*.

Thus a not too heavy, but anyhow rigid spindle upper part is being obtained. The outer part of the spindle may be turned or ground in order to obtain a true running.

5 In case the spindle upper part should exceed a certain length, it may be advantageous to use two pieces of tubes instead of one only. Fig. 2 shows partially such an upper part consisting of one tube *a* and another tube *a*₁, connected by the button *g*, fixed upon the spindle blade. The lower connection of the tube *a* with the whirl and the upper connection of the tube *a*₁ with the button may be made as given in the description referring to Fig. 1.

15 Fig. 3 shows the upper end of another form of an improved spindle upper part. The button *k* is attached to the end of the spindle blade *e*, and is supporting upon its outer surface the tube *a*. The upper end of this tube is closed by the button *l*.

In some cases it may be of advantage to fill the inner space *h* of the tubes with a material of damping character, such as cork, rubber or similar material.

20 25 While the device is herein shown and described as embodied in a preferred form, it is to be understood that the invention may be embodied in other forms without departing from the spirit of the invention.

Having thus described my invention, what I claim is:

1. A spinning or twisting spindle comprising a central support, a whirl connected to one end of the support, having an extension, a button connected to the other end of the support and a central body connected to the support, a tubular body connected to said whirl extension, the button and the said central body, said tube, consisting of two parts having their dividing line located at said central body.

35 40 45 2. A spinning or twisting spindle comprising a central support, a button connected to the upper end of said support, a tubular body extending over said button and support and extending in the other direction beyond said button and means for closing the end of the tube.

WILHELM STAHLCKER.
